[57] ABSTRACT

A jigging machine for treating minerals has a jigging tank with a jigging container and an air chamber. The jigging tank contains water. The air chamber has at least one inlet valve and at least one outlet valve. A compressed air supply is connected to the at least one inlet valve. Compressed air is pulsed via the at least one inlet valve into the air chamber for forcing the water contained in the jigging tank from the air chamber into the jigging container and, after each pulse of compressed air, the water flows back into the air chamber and forces the air out of the air chamber via the at least one outlet valve. The air chamber has an outlet opening positioned below the lowest permissible water level occurring during a jigging pulse. This outlet opening is constantly open during operation of the jigging machine.

FIG-1

AIR-PULSED JIGGING MACHINE WITH SAFETY MEANS AGAINST BLOW THROUGH

BACKGROUND OF THE INVENTION

The present invention relates to an air-pulsed jiggling machine for treating minerals. The device comprises an air chamber for generating the pulsating air stream which has at least one inlet valve for connecting the air chamber to the compressed air supply and at least one outlet valve connected to an exhaust line, whereby via the inlet valve the compressed air is pulsed into the air chamber and the water is forced from the air chamber into the jiggling container. Subsequently, the pulsed air is forced out of the air chamber via the outlet valve due to the water flowing back into the air chamber.

A jiggling machine of the aforementioned kind is disclosed in particular with respect to its function in German Patent Application 36 22 551. Different embodiments of such jiggling machines are known, for example, from Schubert "Aufbereitung fester mineralischer Rohstoffe", Vol. II, VEB Deutscher Verlag für Grundstoffsindustrie, Leipzig, 3rd edition, pp. 83 and 86, wherein the air chamber of so-called laterally pulsed jiggling machines are arranged laterally with respect to the jiggling container and in so-called BATAc jiggling devices are positioned below the jiggling container, respectively, jiggling bed. In both designs of air-pulsed jiggling machines the risk of blow through is present which occurs when during the jiggling pulse the introduced compressed air forces the water level of the jiggling water within the air chamber below the lowest permissible level so that the pulsed air can transfer from the air chamber directly into the jiggling container.

It is therefore an object of the present invention to provide a jiggling machine of the aforementioned kind with which blow through can be prevented.

SUMMARY OF THE INVENTION

A jiggling machine for treating minerals according to the present invention is primarily characterized by:

A jiggling tank comprising a jiggling container and an air chamber;

The jiggling tank containing water;

The air chamber having at least one inlet valve and at least one outlet valve;

A compressed air supply connected to the at least one inlet valve, wherein compressed air is pulsed via the at least one inlet valve into the air chamber for forcing the water contained in the jiggling tank from the air chamber into the jiggling container wherein after each pulse of compressed air the water flows back into the air chamber and forces the air out of the air chamber via the at least one outlet valve; and

Wherein the air chamber comprises an outlet opening positioned below the lowest permissible water level occurring during a jiggling pulse, the outlet opening being continuously open during operation of the jiggling machine.

Advantageously, the jiggling machine further comprises a valve for controlling an opening cross-section of the outlet opening.

According to the present invention, the air chamber is provided with an outlet opening positioned below the lowest permissible water level of the jiggling pulse. This outlet opening is maintained open constantly during operation of

the jiggling machine. This results in the advantage that upon falling below the lowest permissible level (i.e., before an actual blow through occurs), the outlet opening is freed from the water column which during normal operation of the jiggling machine covers the outlet opening so that the excess of compressed air, respectively, the compressed air which is still being introduced can be removed from the jiggling tank via this outlet opening without forcing the water level within the air chamber to a level at which blow through would occur. In order to avoid the otherwise required control expenditure, the outlet opening during the operation of the jiggling machine is constantly maintained open so that during operation a small amount of water constantly exits through the outlet opening. The invention uses the knowledge that for an open outlet opening approximately the tenfold amount of air can be guided therethrough as compared to the amount of water which exits therethrough during normal operation of the jiggling machine so that a correspondingly small opening cross-section is sufficient in order to provide for a sufficient amount of air being expulsed from the air chamber in dangerous situations.

According to one embodiment of the invention the outlet opening is controlled with respect to its opening cross-section by a valve. It can furthermore be provided that the water, which continuously exits via the outlet opening during operation of the jiggling machine, is recirculated at a suitable location of the system.

BRIEF DESCRIPTION OF THE DRAWINGS

The object and advantages of the present invention will appear more clearly from the following specification in conjunction with the accompanying only drawing, showing an air-pulsed jiggling machine in the embodiment of a laterally pulsed jiggling device in a schematic side view.

DESCRIPTION OF PREFERRED EMBODIMENT

The present invention will now be described in detail with the aid of a specific embodiment utilizing the only Figure.

The jiggling container 10 of a jiggling tank of a jiggling machine has coordinated therewith an air chamber 11 which is connected via an inlet line 12 to the air tank 13 for supplying the air chamber 11 with compressed air. A rotary piston slide valve 18 is positioned within the inlet line 12 which functions alternately as an inlet valve and outlet valve whereby the outlet side of the jiggling machine is not represented in the drawing. At 14 the average working level of the jiggling water level during normal operation of the jiggling machine is shown, and the dashed line 15 indicates the lowest permissible level of the water within the air chamber. The water level should not drop below level 15 to a greater extent when blow through of the jiggling machine is to be prevented. Directly below the level 15 an outlet opening 16 is arranged within the air chamber 11. This opening 16 is controllable by a valve 17. The valve 17 is open constantly during operation of the jiggling machine.

When during the jiggling pulse the water level of the jiggling water is pushed in the direction of the jiggling container 10 to a level at which the risk of blow through of the pulsed air within the air chamber 11 into the jiggling container 10 is present, the water level which is falling now frees the outlet opening 16 within the air chamber 11 which is arranged at the corresponding safety level so that via this outlet opening 16, respectively, the slightly opened valve 17 the pulsed air can flow out without forcing the water level within the air chamber 11 below the critical level.

The shown arrangement can be used in the same manner for laterally pulsed as well as for bottom-pulsed jiggling machines.

The present invention is, of course, in no way restricted to the specific disclosure of the specification and drawings, but also encompasses any modifications within the scope of the appended claims.

What I claim is:

1. A jigging machine for treating minerals, said jigging machine comprising:

a jigging tank comprising a jigging container and an air chamber;

said jigging tank containing water;

said air chamber having at least one inlet valve and at least one outlet valve;

a compressed air supply connected to said at least one inlet valve, wherein compressed air is pulsed via said at least one inlet valve into said air chamber for forcing

5

10

the water contained in said jigging tank from said air chamber into said jigging container and wherein after each pulse of compressed air the water flows back into said air chamber and forces the air out of said air chamber via said at least one outlet valve; and

wherein said air chamber comprises an outlet positioned below a lowest possible water level occurring during a jigging pulse, said outlet being continuously open during operation of said jigging machine to allow pulsed air to escape in order to prevent blow through.

2. A jigging machine according to claim 1, further comprising a valve for controlling an opening cross-section of said outlet.
